Method and apparatus for holding offset master sheets during treatment such as cleaning, preserving, or developing, comprising a pair of flat panels hinged together at one edge, each panel having a support member attached to a free end thereof, and a clamp plate hinged to each support member, the clamp plate being adapted to grip an offset master sheet along an edge thereof, and a link connecting the clamp plates.

UNITED STATES PATENT OFFICE

2,561,501

RACK FOR HOLDING OFFSET MASTER SHEETS

Fred H. Davis, Hamilton, Ohio

Application May 12, 1949, Serial No. 92,781

5 Claims. (Cl. 101—131)

1

This invention relates to a rack adapted for holding an offset master sheet or the like during treatment such as cleaning, preserving, or developing the master.

In one type of offset printing, copy is set up on a flexible master sheet. The copy is inked and the ink transferred to an offset roll which does the actual printing. Master sheets, which may be made of thin flexible sheet material such as zinc, aluminum, paper or plastic, may be cleaned and reused. However, the cleaning process requires sponging of the copy surface with appropriate solvents, and during sponging the master sheet must be held firmly at both ends.

An object of this invention is to provide a rack constructed to hold an offset master sheet during sponging or other treatment.

A further object of this invention is to provide a rack having clamps adapted to engage both ends of a master sheet to hold the master sheet flat and smooth during treatment.

In the use of photo-sensitized masters, it is necessary to sponge a sensitized surface with appropriate photographic developers, and a further object of this invention is to provide a rack for holding a photo-sensitized offset master sheet during sponging.

The above and other objects and features will in part be obvious and will in part be apparent from the following detailed description and the drawings, in which:

Figure 1 is a view in side elevation showing a rack constructed in accordance with an embodiment of this invention;

Fig. 2 is a bottom plan view of the rack illustrated in Fig. 1;

Fig. 3 is a fragmentary view in side elevation showing the rack with a clamp plate thereof in released position; and

Fig. 4 is a view in end elevation of the rack.

In the following detailed description and the drawings, like reference characters indicate like parts.

As shown in the drawings, the rack includes a pair of flat panels 10 having adjoining edges hinged together by hinges 12. A free end 13 of each panel is bent at an obtuse angle thereto to form a supporting member. Buttons 14 of rubber or the like are attached to the support members 13 by means of angular legs 16, and the buttons 14 serve to support the panels.

A clamp plate 17 is hinged at the free edge of each support member 13. Each clamp plate includes a main section 18 and a flange 19. Each flange 19 is adapted to swing toward one of the

panels 10 to grip an offset master sheet 20 along an edge thereof as shown in Fig. 1. A handle 21 is welded or otherwise firmly attached to each clamp plate for raising the clamp plate from the panel 10.

Each clamp plate is further provided with a pair of lugs 22 extending substantially perpendicularly to the plate, a lug being located at each side of the clamp plate and being formed from a section of the clamp plate bent away from the plane of the clamp plate. The lugs 22 extend through slots 23 in the support members, and the lugs of opposite clamp plates are joined by links 24. As shown in Figs. 1 and 3, the panels 10 meet in a peak at the hinges 12, and the panels and links 24 form a toggle linkage. When hinges 12 are pushed towards links 24 to place the panels 10 in alignment, the clamps are pulled tightly against the edges of the offset master sheet to hold the master sheet firmly in place in flatwise relation upon the panels.

When the master sheet 20 is held in place upon the panels 10, it is firmly held at both ends and may readily be sponged with appropriate cleaning fluids, chemical developers or the like.

The hinges 12, as shown in Fig. 1, are so formed that when the panels approach alignment, the hinges bind to prevent the toggle linkage formed by panels 10 and links 24 passing dead center.

The rack may be readily constructed of sheet metal parts or the like, and the clamp plates 17 are preferably formed of resilient metal so that when the panels are pushed toward aligned position, the clamps resiliently grip the edges of the master sheet and as pressure on the panels is increased, the grip is tightened.

The embodiment of the invention described above and illustrated in the drawing is subject to structural modification without departing from the spirit and scope of the appended claims.

Having described my invention, what I claim as novel and desire to secure by Letters Patent is:

1. A rack for holding offset master sheets which comprises a pair of adjoining flat panels, adjacent edges of said panels being hinged to each other, a support member attached to the free end of each panel, said support members being adapted to support the panels, a clamp for each support member, each clamp including a pivot arm hinged to one of the support members and a clamp arm adapted to engage one of the panels and grip an offset master sheet along an edge thereof, and a link connecting said clamps, said panels being angularly inclined to each

other when said clamps are open, the connection between each clamp and the link being between the panel hinge and the clamp pivot, the link pulling said clamps against the panels when the panels are moved into straight line position, whereby the clamp arms are adapted to grip opposite edges of the master sheet and hold the master sheet in flatwise relation to the panels.

2. A rack for holding offset master sheets which comprises a pair of adjoining flat panels, adjacent edges of said panels being hinged to each other, a support member attached to the free end of each panel, said support members being adapted to support the panels, a clamp for each support member, each clamp including a pivot arm hinged to one of the support members and a clamp arm adapted to engage one of the panels and grip an offset master sheet along an edge thereof, and a link connecting said clamps, said panels being angularly inclined to each other when said clamps are open, the connection between each clamp and the link being between the panel hinge and the clamp pivot, the link pulling said clamps against the panels when the panels are moved into straight-line position, whereby the clamp arms are adapted to grip opposite edges of the master sheet and hold the master sheet in flatwise relation to the panels, the hinge between the panels being adapted to bind when the panels are in alignment to limit downward displacement of the panels.

3. A rack for holding an offset master sheet which comprises a pair of adjoining flat panels, adjacent edges of said panels normally meeting at a peak and being hinged to each other, a support member attached to the free end of each panel and extending at an obtuse angle to the panel, said support members being adapted to support the panels, a clamp for each support member, each clamp including a pivot arm hinged to one of the support members and a clamp arm adapted to engage one of the panels and grip an offset master sheet along an edge thereof, each of said clamps being formed of resilient metal, and a link connecting said clamps, the connection between each clamp and the link being between the panel hinge and the clamp pivot, said panels being angularly inclined to each other when said clamps are open, said link pulling the clamps against the panels when the panels are moved into straight line position, whereby the clamp arms are adapted to grip opposite edges of the master sheet resiliently and hold the master sheet in flatwise relation to the panels.

4. A rack for holding an offset master sheet which comprises a pair of adjoining flat panels, adjacent edges of said panels normally meeting at a peak and being hinged to each other, a sup-

port member attached to the free end of each panel integral with and extending at an obtuse angle to the panel, said support members being adapted to support the panels, a clamp for each support member, each clamp including a pivot arm hinged to one of the support members and a clamp arm adapted to engage one of the panels and grip an offset master sheet along an edge thereof, each of said clamps being formed of resilient metal, and a link connecting said clamps, the connection between each clamp and the link being between the panel hinge and the clamp pivot, said panels being angularly inclined to each other when said clamps are open, said link pulling the clamps against the panels when the panels are moved into straight line position, whereby the clamp arms are adapted to grip opposite edges of the master sheet resiliently and hold the master sheet in flatwise relation to the panels.

5. A rack for holding an offset master sheet which comprises a pair of adjoining flat panels, adjacent edges of said panels normally meeting at a peak and being hinged to each other, a support member extending at an obtuse angle from the free end of each panel, said support members being adapted to support the panels, a clamp for each support member, each clamp extending substantially across one of the panels and including a pivot arm hinged along a lower side of one of the support members to swing toward and away from the support member and a clamp arm adapted to engage one of the panels, a pair of lugs attached to the pivot arm of each clamp, each of said lugs extending beyond the support member to which the pivot arm is hinged adjacent a side of the rack, and a pair of links, each link extending between the lugs of opposite clamps, the connection between each lug and link being between the panel hinge and the pivot of the clamp to which the lug is attached, said panels being angularly inclined to each other when said clamps are open, the links pulling said clamps against the panels when the panels are moved into straight line position, whereby the clamp arms are adapted to grip opposite edges of the master sheet to hold the master sheet in flatwise relation to the panels.
